UNITED STATES PATENT OFFICE.

EMORY J. LIPPS, OF FOUNTAIN HILL BOROUGH, PENNSYLVANIA.

TENSION MEANS.

Application filed September 8, 1924. Serial No. 736,523.

To all whom it may concern:

Be it known that I, EMORY J. LIPPS, a citizen of the United States, residing at borough of Fountain Hill, in the county of 5 Lehigh and State of Pennsylvania, have invented certain new and useful Improvements in Tension Means, of which the following is a specification.

This invention relates to mechanism 10 whereby yarn is drawn from a spool or bobbin endwise thereof for any purpose, as in spinning or doubling, and in being so drawn wipes around an endless yarn-guiding surface, as of the head or flange of the bobbin. 15 or of a ring concentric with the bobbin. The principal object of the invention is to provide means whereby an equable tension may be imposed on the yarn at all times, or regardless of the reduction in diameter 20 of the wound mass from which it is drawn that accompanies the withdrawal of the yarn. Another object is to provide an improved means for stopping the drawing of the yarn on breakage or undue slackness of 25 the yarn or to its opposing undue resistance to the draft.

In the drawings,

Fig. 1 is a vertical sectional view of a machine embodying the invention;

30 Fig. 2 is a front elevation of what is seen in Fig. 1;

Fig. 3 is a plan of the principal elements involved in the invention;

35 Fig. 4 is a side elevation of said elements; and

Fig. 5 is a front elevation of certain of the elements shown in Figs. 4 and 5.

On the frame 1 is arranged suitable draft 40 means for the yarn, the same comprising a spool or bobbin 2 journaled in brackets 3

of the frame on a horizontal axis and a whirl 4 fixed on a suitably rotated horizontal shaft 5 and on which the spool 2 is adapted to peripherally rest and by which it is 45 rotated; the draft means may include a guide 6 whereby the draft on the yarn is directed toward a point displaced longitudinally of the axis of the wound mass from which the yarn is drawn. There may also

50 be means to lay the yarn windings on spool 2 back and forth lengthwise of its axis, as the usual reciprocated traverse rail 7 having a yarn guide 8.

55 The wound mass from which the yarn is drawn is indicated at 9, its support being here a spool or bobbin 10 which is set upon

a vertical tubular spindle 11 (Fig. 4) up-standing from a bracket 12 of the frame 1 below the spool 2. The already mentioned endless yarn-guiding surface around which the yarn A wipes in being drawn from spool 10 by the draft means is here afforded by a ring 13 (of I-shaped cross-section, see Fig. 4) around which is freely movable a traveller-guide 14 for the yarn, such ring being the peripheral part of a skeleton cap 15 which is fitted over the head of the spool and thereby kept in operative position, having a central hole 15^a the purpose of which will appear. An auxiliary endless yarn guiding surface 16, encompassing a space 17, is afforded by an annular part 18 up-standing from the cap concentrically thereof. I prefer to embody the two yarn-guiding surfaces in a single structure as described and shown, but of course this is not indispensable.

A movable tension device with which the yarn has running engagement between the auxiliary yarn-guiding surface and the draft means and which is normally urged toward the wound mass but is yieldable therefrom under the tension of the yarn and has its yarn-engaged portion enterable into the space 17 is here afforded by a light lever 19 fulcrumed in the frame at 20 to move up and down and having as its thread-engaged portion the eye 19^a adapted, on account of a suitable upward bend 19^b in the lever, to enter the space 17; this lever is in the present case normally urged toward the wound mass 9 by gravity and for regulating its tendency thus to move subject to gravity it may have a nut 21 screwed thereon and serving as an adjustable counter-weight.

It will be seen that in the absence of the auxiliary yarn-guiding surface 16 when the spool is full (i. e., when the wound mass 9 has its maximum diameter) the resistance 100 of the yarn to the draft is least and when the spool is empty such resistance is greatest. This produced such a disparity between the tension at the start and that at the end of the unwinding of the mass 9 (in itself of course objectionable) that where automatic stopping means dependent on tension of the yarn was employed, it was heretofore impossible to carry on the operation without automatic stopping occurring 105 due merely to such disparity, especially where weak yarn was being operated upon 110

and the tension device, such as 19 or its equivalent, therefore had to be very sensitive in its action. By providing the auxiliary yarn-guiding surface 16 I overcome 5 this difficulty. When, with surface 16 present, the tension incident to the wiping of the yarn around the yarn-guiding surface of ring 13 is least because the spool is then full such tension is augmented by that 10 produced by the tension device being then allowed to assume its most depressed position, where its eye 19^a holds the yarn in a bend over the surface 16; when the tension incident to the wiping of the yarn around 15 the said surface of ring 13 is greatest because the spool is nearly empty the augmenting tension is reduced, the tension device being then elevated to the dotted position in said figure so that the bend of the 20 yarn over surface 16 is reduced. I am thus able to obtain equitable or substantially perfect tension on the yarn at all times throughout the delivery of the yarn from the package, and reduce automatic stopping 25 of the operation to instances where the yarn breaks or there is a localized laxity in the windings of the mass 9 or to some convolution of the windings catching and failing to deliver.

30 For automatically stopping the winding due to any of these latter causes I have devised the improved means shown best in Figs. 3, 4 and 5. The lever 19 has a projecting blade 19^c thereof penetrated by a vertical rod 22 carrying above and below and normally spaced from the blade the collars 22^a. This rod depends from the arm 23^a of a lever 23 fulcrumed on a horizontal axis in the frame 1 and normally held 35 lightly bearing against any suitable stop 24 by a weight 23^b, so that a blade 23^c of the lever is in the retracted position shown by full lines in Fig. 4. When, due to breakage or undue slackness in the yarn, the tension device falls unduly and so presses 40 upon the lower collar 22^a, the rod will be depressed and tilt lever 23 past its center of gravity, which then thrusts its blade 23^c between the spool 2 and its whirl 4, thereby 45 stopping the rotation of the spool. The rod has another collar 22^b which underlies the forked end of a lever 24 fulcrumed on a stud 24^a in the frame, the other end of this lever being connected by a link 25 with a 50 lateral extension 23^x of arm 23^a of lever 23. When, due to unusual resistance of the 55 yarn to draft, as if some convolution of the yarn catches in the mass 9 and fails to deliver, the tension device rises and so encounters the upper collar 22^a the rod will 60 be elevated and, acting through lever 24, tilt lever 23 to cause the stopping as before.

I have shown the invention in Figs. 1 and 2 in a system where several yarns (or 65 strands) are combined to form a single yarn

and are supplied from several spools 10 arranged one above another, each yarn from a relatively lower spool extending up through the tubular spindle 11 and cap-hole 15^a for the spool above so that they 70 may all be incorporated one after another into the final yarn with an incidental winding of each around the yarn that comes from below. This I show not because it is in itself new but because it illustrates an application of my invention in which it has been successfully used and in which it is extremely necessary to maintain the tension of the component yarns equitable at all 75 times.

Having thus fully described my invention, what I claim as new and desire to secure by Letters Patent is:

1. In combination, means to support a mass of yarn arranged in convolutions 85 around a common axis, means to draw the yarn from the mass toward a point displaced from the package longitudinally of its axis, an endless yarn-guiding surface arranged around said axis near the end of the 90 mass adjoining the draft means and around which the yarn wipes when subject to the draft of the draft means, an auxiliary endless yarn-guiding surface arranged around said axis between the first surface and said 95 draft means and around which the yarn also wipes when subject to the draft of the draft means, said auxiliary surface encompassing a free space, and a movable tension device with which the yarn has running engagement between the auxiliary surface and the draft means, said device being normally urged toward the mass but yieldable therefrom under tension of the yarn and having its yarn-engaged portion enterable into said 100 space.

2. In combination, means to support a mass of yarn arranged around a common axis and with said axis upright, means to draw the yarn from the mass to a point 110 above the same, an endless yarn-guiding surface arranged around said axis near the upper end of the mass and around which the yarn wipes when subject to the draft of the draft means, an auxiliary endless yarn-guiding surface arranged around said axis between the first surface and said draft means and around which the yarn also wipes when subject to the draft of the draft means, said auxiliary surface encompassing 115 a free space, and a movable tension device with which the yarn has running engagement between the auxiliary surface and the draft means, said device being normally held downward but yieldable upward under tension of the yarn and having its yarn-engaged portion enterable into said space.

3. In combination, a frame, a wound body arranged on the frame and having its windings arranged around a common vertical 120

axis, means to draw the yarn from said body to a point above the same, a yarn-guiding structure supported on said body and including upper and lower endless yarn-guiding surfaces around which the yarn winds in being drawn from said body by the draft means, the upper one of said surfaces encompassing a free space, and a movable tension device with which the yarn has running engagement between said upper endless surface and the draft means, said device being normally held downward but yieldable upward under tension of the yarn and having its yarn-engaged portion enterable into said space.

4. In combination, a frame, means to support a wound body therein, means to draw the yarn from said body, a stopping device for the second means movable into engagement therewith to stop the same upon application of force thereto in a given direction, a member movable in said direction to apply such force to said device and also in the reverse direction, means to transmit

force from said member to said device in said direction when said member moves in the reverse direction, and a back-and-forth-movable tension device engaged by the yarn and adapted on movement in either direction to move said member one way or the other. 25 30

5. In combination, a frame, means to support a wound body therein, means to draw the yarn from said body, a stopping device for the second means movable into engagement therewith to stop the same upon application of force thereto in a given direction, a member movable in said direction to apply such force to said device and also in the reverse direction, a lever to transmit force from said member to said device in said direction when said member moves in the reverse direction, and a back-and-forth-movable tension device engaged by the yarn and adapted on movement in either direction to move said member one way or the other. 35 40 45

In testimony whereof I affix my signature.

EMORY J. LIPPS.
